UNITED STATES PATENT OFFICE

FRED A. PUTNAM, OF KEENE, NEW HAMPSHIRE, ASSIGNOR TO MARKEM MACHINE COMPANY, OF BOSTON, MASSACHUSETTS, A CORPORATION OF MASSACHUSETTS

TYPE CHASE

Application filed April 23, 1927. Serial No. 185,987.

This invention relates to a type chase for use in printing machines and has for its object to provide a novel type chase which is specially designed for use in printing labels for shoe boxes or for printing the name of the shoe and other data directly on the end of the shoe box.

It is the common practice in retail shoe stores to keep each pair of shoes in a separate box, each box being marked to indicate the style, size and character of the shoe contained therein. Sometimes this data is printed on a label which is pasted on the end of the box and sometimes the data is printed directly 15 on the box end.

A machine specially designed for printing directly on box ends is illustrated in United States Patents No. 1,279,904, September 24th, 1918, and No. 1,390,388, September 13th, 1921.

20 The machines shown in these patents include a printing couple comprising a platen over which the box may be placed with the end of the box resting against the platen surface and a printing head carrying the printing elements and means to move the platen and printing head toward and from each other to make the printed impression directly on the end of the box. The printing element shown in the patents is in the form of a 25 type chase carrying type members which are locked in a frame so that no change in the character of the printed matter can be made without removing the type chase from the printing head and then resetting the type. 30 Such a machine is well adapted for printing on the end of the shoe boxes the name of the shoe and the manufacturer's name or some other similar data which goes on all shoe boxes.

35 The shoe boxes which are used in a retail store, however, not only have printed thereon the name of the shoe and the name of the manufacturer, etc. but each box has some special data printed thereon descriptive of the particular pair of shoes in the box. Such variable data is sometimes written on the box by hand.

40 One of the objects of my present invention is to provide a novel type chase by which both 45 the variable data, such as the size and width

of the shoe, case number, stock number, etc. and the non-variable data, such as the name of the shoe and the name of the manufacturer, etc. can be printed on the box end at one operation.

55 The type chase is so constructed that the type members by which the variable data is printed on the box end can be readily changed or reset without removing the type chase from the printing head and with a minimum amount of labor and with a minimum expenditure of time.

In order to give an understanding of the invention I have illustrated in the drawings a selected embodiment thereof which will now 65 be described after which the novel features will be pointed out in the appended claims.

Fig. 1 is a view of a type chase embodying my invention;

70 Fig. 2 is a fragmentary sectional view showing the printing couple of a machine such as shown in the abovementioned Patents No. 1,279,904 and No. 1,390,388 with my improved type chase therein;

Fig. 3 is an enlarged section on the line 75 3—3, Fig. 1;

Fig. 4 is a similar section but showing the locking member in released position;

Fig. 5 is a perspective view of one of the interchangeable type elements;

80 Fig. 6 is an enlarged section on the line 6—6, Fig. 1;

Fig. 7 is a fragmentary perspective view of the end of a box on which a printed impression has been made in accordance with 85 this invention.

Referring first to Fig. 2, 1 indicates a platen such as shown in the above-mentioned patents and which is adapted to have a box 90 placed thereover with the end 3 of the box resting against the platen surface, this being the end on which the printed impression is to be made. 4 indicates a printing head which carries a type chase 7 in which is received a printing block or printing members 6 by which the printed impression is 95 made.

The printing couple, comprising the platen 1 and printing head 2, are shown in Fig. 2 in the position they occupy when making the 100

printed impression, it being understood that these elements 1 and 4 are movable toward and from each other as usual with printing couples.

5 The type chase with which the present invention is concerned comprises the usual skeleton make-up frame 7 adapted to receive type members which may be separate type or a block 8 bearing type characters, the type 10 member or members being locked in the frame 1 by quoins 9 in usual manner.

The parts thus far described are or may be all as usual in printing machines.

According to the present invention one 15 side of the frame 7 is so constructed that separate interchangeable type elements 10 may be set or placed thereon or removed therefrom while the frame is held in the printing head, such type elements when in place 20 being positioned properly to make a printed impression on the box end 3 simultaneously with the type which is located in the frame. These interchangeable type elements 10 may bear type characters representing figures, 25 letters or words and they are so mounted on the side of the frame that they can be easily changed to produce different printed impressions without removing the type chase from the printing head.

30 In the illustrated embodiment of the invention the side 11 of the frame 7 is formed with a type-holding rib 12 on which the interchangeable type elements 10 are mounted.

Each type element 10 is formed with the 35 slot 13 and it is provided on its face 14 with a type character 15, said face 14 being so situated that when the type member is mounted on the rib 12 as shown in Figs. 3 and 4 the type character 15 occupies the same 40 plane as the type characters 6.

To facilitate the handling of the interchangeable type members 10 each is provided with an upstanding extension or finger piece 16 by which it may be manipulated. The 45 type members are locked on the type-holding rib 12 by means of a locking bar 17 which is pivoted to the side 11 of the frame as shown at 18, said locking bar having at its upper edge a lip 19 adapted to overlie the shoulder 50 20 of each type element 10. This locking bar is provided with a handle 21 by which it may be swung from its operative position shown in Fig. 3 to its inoperative position shown in Fig. 4. When in its inoperative 55 position the type members are all released and can be readily removed from the rib 12 and thus any desired change in the type members may be made.

Associated with the type members 10 are 60 spacers 22 which are adapted to be clamped to the rib 12 by set screws 23 and which may be used to provide the required spacing between words and groups of numerals and also to hold the type members in desired 65 position. These spacers are simply U-

shaped members adapted to fit over the rib 12 and carrying the set screws 23 to bind against the rib.

The type members 10 may each have thereon a type character representing a single 70 letter or figure. Some type members may have thereon a series of type characters to print a word, such for instance as "Oxford" or "Kid".

In the set up shown in the drawings there 75 is one group of type members 10 arranged to print "9057E" and another single type member having type characters thereon to print the word "Oxford"; another group of type members 10 adapted to print "328A"; another type member 10 having the type character thereon adapted to print the word "Kid" and a type character adapted to print the figure "2". The groups of type members and the type members representing words are 80 separated by suitable separators 22.

In printing on the end of a box where the box is turned bottom side up over the platen as shown in Fig. 2 the printing characters will have to be inverted in order that the 90 printed impression may be upright when the box is in its normal position. With the construction herein shown wherein the upper side 11 of the frame 7 carries the type members 10 the printed impression made by the 95 type members 10 will be located on the box below that made by the printing block 8, and thus the data representing the style, size, case number and character of a shoe is on a line at the bottom of the box which is in accordance 100 with the best practice.

With this construction the type members 10 can be easily and quickly set up on any type chase to print any desired data on the box without removing the type chase from the 105 printing head 4. When a change in the printed impression made by the type members 10 is desired the locking member 17 can be swung into its inoperative position shown in Fig. 4 and the type members 10 which are to be 110 changed can be readily removed and replaced by different ones, this change requiring only a very small space of time. When the change has been effected the type members 10 are relocked in position by swinging the locking bar 115 115 back into the position shown in Fig. 3.

The invention is very simple in construction but makes it possible to print at one operation both the unvarying data, such as the trade name of the shoe and the manufacturer's name, etc., and also the variable data, such as the case number, style, size, stick number, etc. Further the invention is such that this variable data can be printed at the lower portion of the side of the box beneath the main 120 printed impression according to the best practice.

I claim:

1. A type holder comprising a type-holding frame having an exterior type-holding 125 frame having an exterior type-holding

rib, type members each having a forked body portion to fit over the rib, and a locking bar pivoted to the frame to turn about an axis parallel to the rib and when in operative position engaging the type members and locking them to the rib.

2. A type holder comprising a type-holding frame having an exterior rib, interchangeable type members each having a forked body portion to fit the rib and also each provided with a shoulder and a locking bar pivoted to the frame and adapted to engage the shoulders of the type members on the rib thereby locking said members in position.

3. A type holder comprising a frame having an exterior rib, a plurality of type members each having a forked body to fit over the rib and an extension constituting a finger piece by which the type members can be handled, and means to lock the type members to the rib.

4. A type holder comprising a frame having an exterior rib, a plurality of type members each having a forked body to fit over the rib, a shoulder and an extension constituting a finger piece by which the type member can be handled, and a locking bar pivoted to the frame and adapted to engage the shoulders of the type members and lock them in position on the rib.

5. A type holder comprising a skeleton make-up frame adapted to hold ordinary type within it, said frame having a rib extending along one side thereof on its exterior, type members straddling said rib and having printing faces which are in the plane of the printing faces of the type within the frame, and a locking member pivoted to the frame to turn about an axis parallel to the rib and when in operative position locking the type members on the rib.

6. A type holder comprising a skeleton make-up frame having an open center in which ordinary type may be placed with their printing faces exposed on one side of the frame and their opposite faces exposed on the other side, said frame having on its exterior means for removably holding separate type elements with their printing faces in the plane of the printing faces of the type situated within the frame.

7. A type holder comprising a skeleton make-up frame having an open center in which ordinary type may be placed with their printing faces exposed on one side of said frame and their opposite faces exposed on the other side thereof, said frame having a type-holding rib on its exterior, interchangeable type members straddling said rib and removably retained thereon, and means to lock the interchangeable type members to the rib.

In testimony whereof, I have signed my name to this specification.

FRED A. PUTNAM.
